UNITED STATES PATENT OFFICE.

PAUL W. FENTON, OF NEW YORK, N. Y.

PRICE-EXHIBITING DEVICE.

Application filed May 7, 1925. Serial No. 28,541.

To all whom it may concern:

Be it known that I, PAUL W. FENTON, a citizen of the United States, residing at New York, in the county of New York and State of New York, have invented certain new and useful Improvements in Price-Exhibiting Devices, of which the following is a specification.

The invention relates to changeable signs designed, for example, as price indicating means, such as may be utilized in exhibiting the price of gasoline at a filling station.

It has for its object to provide a substantial though cheaply manufactured device of this character which shall be compact and afford ample variation in the particular indicia employed, for example, over the prevailing range of prices. A further object of the invention consists in providing means whereby a particular indicator member may be quickly and readily selected or changed.

The nature of the invention, however, will best be understood when described in connection with the accompanying drawings, in which—

Fig. 1 is a front elevation of the improved exhibiting device shown suspended from a suitable bracket.

Fig. 2 is a front elevation of the said device with the forward cover plate removed.

Fig. 3 is a vertical transverse section taken on the line 3—3, Fig. 2, looking in the direction of the arrows.

Referring to the drawings, the novel device comprises a suitable casing or housing composed of a front member 10 and a back member 11 having corresponding flanged edges designed to fit one within the other to provide a casing or housing for display members hereinafter described. These housing members are provided, furthermore, with registering windows or sight openings 12 and 13 cut therein; and the members are preferably of sheet metal but may be of other material sufficiently durable to withstand the wear to which the exhibiting device is to be subjected.

Upon either side of the windows 12 and 13 and within the housing is pivotally mounted a set of plates 14 and 15 which bear the figures or other indicating marks which it is desired to display thru the said windows, both faces of a plate being provided with similar marks and the two sets of plates upon opposite sides of the window provid-

ing, for example, consecutive numbers representing a price or the like.

It will be understood, of course, that but a single set of plates may be employed but the thickness of the housing will be correspondingly increased.

Each set of plates is mounted in a U-shaped container 16 and 17, respectively, fitting over the lower edges thereof and being secured thereto by respective rivets 18 and 19 passing thru the walls of the corresponding U-shaped members and the plates at their lower corner near the edge adjacent the windows 12 and 13. These rivets are extended thru both of the frame members to secure the plates thereto in symmetrical position upon opposite sides of the median line of the windows and to provide, also, pivot pins or studs upon which the said plates may be swung to bring the same in exhibiting position before the windows. It will be understood that one plate only from a particular side is to remain in horizontal position to register with the windows, the plates of each set being marked to correspond to the range of figures required. Moreover, all of the plates except those in use will normally be concealed within the housing and be retained in a substantially vertical position thru the action of gravity in view of the pivoting of such plates at the lower corner near the edge adjacent the window. Suitable legends and other information may, of course, be also displayed in connection therewith upon the outer faces of the housing, as indicated, being embossed thereon or cut therein or otherwise applied.

To exhibit the desired slide or plate, it is necessary to swing an entire set across the window and then return the individual plates manually with the exception of the particular one selected. In accordance with the invention, provision is made for conveniently upsetting or swinging all of the plates of a set, as contained by its U-shaped members, simultaneously into horizontal position before the windows. This is effected by push rods 20 or like members projecting outwardly from the bottom of the housing and preferably mounted in a block 21 at the lower portion of the housing between its walls and which may serve as a bearing for said rods and a stop for the plates when horizontally disposed and may be of wood or other inexpensive material. The inner end of a push rod is turned over

for this purpose and to prevent withdrawal of the push rod from the housing, said end affording thus a substantial contact surface with the bottom of a U-shaped member 16 or 5 17. The push rods are offset some distance from the corresponding pivot studs 18 or 19 of a set of plates so as to afford ample leverage in the swinging of such set, this being accomplished by pressing upwardly on 10 the outer head 22 of the corresponding push rod. In this manner, the battery of plates is rendered conveniently available and from which the desired one is selected thru a window as hereinbefore set forth.

15 As the exhibitor device may in many instances be employed in positions where it is subject to the elements, it is desirable to provide a drain opening 23 thru the block 20 in addition to such openings as may be about 20 the push rods. Suitable attaching means 24, also, are provided at the upper portion of the device whereby the same may be secured to a convenient bracket or like member, as indicated in Fig. 1.

25 I claim:—

1. A price exhibitor comprising a housing and marked plates mounted therein, and the said housing being provided with a window, and means to simultaneously move all 30 the plates into position before the window to permit of selecting a desired plate therefrom to remain in exhibiting position.

2. A price exhibitor comprising a housing and two sets of marked plates mounted 35 therein at opposite sides, and the said housing being provided with an intermediate window, and means to simultaneously move all of the plates of a particular set into position before the window to permit of selecting a desired plate therefrom to remain in 40 exhibiting position.

3. A price exhibitor comprising a hous-

ing and two sets of marked plates mounted therein at opposite sides, and the said housing being provided with an intermediate 45 window, a U-shaped holding member for each set of the plates, means to pivot said members with plates to the housing, and push rods extending beyond the housing and having their inner ends in proximity to the 50 U-shaped members and adapted to engage the same for upsetting a set of plates.

4. A price exhibitor comprising a housing and two sets of marked plates mounted therein at opposite sides, and the said housing being provided with an intermediate window, a U-shaped holding member for 55 each set of plates, means to pivot said member with plates to the housing at the lower corner near the adjacent edge of the window, and push rods extending beyond the housing and having their inner ends adapted to engage the U-shaped member at point removed from the pivot studs for upsetting a set of plates.

5. A price exhibitor comprising a housing and two sets of marked plates mounted therein at opposite sides, and the said housing being provided with an intermediate window, a U-shaped holding member for 70 each set of the plates, means to pivot said members with plates to the housing, a block of material held between the walls of the housing at its lower portion acting as a stop for the plates when swung into position before the window, and push rods fitting to 75 said blocks, extending beyond the housing and have their inner ends in proximity to the U-shaped members and adapted to engage the same for upsetting a set of plates. 80

In testimony whereof I affix my signature.

PAUL W. FENTON.
